M. TIBBETTS.
REFRIGERATING APPARATUS,
APPLICATION FILED AUG. 19, 1916.

1,312,932.

Patented Aug. 12, 1919.

Witness:

J. C. L. Blackmore.

Inventor:

Milton Tibbets.

UNITED STATES PATENT OFFICE.

MILTON TIBBETTS, OF DETROIT, MICHIGAN, ASSIGNOR, BY MESNE ASSIGNMENTS, TO THE ISKO COMPANY, OF CHICAGO, ILLINOIS, A CORPORATION OF DELAWARE.

REFRIGERATING APPARATUS.

1,312,932.

Specification of Letters Patent.

Patented Aug. 12, 1919.

Application filed August 19, 1916. Serial No. 115,837.

To all whom it may concern:

Be it known that I, MILTON TIBBETTS, a citizen of the United States, and resident of Detroit, Wayne county, State of Michigan, have invented certain new and useful Improvements in Refrigerating Apparatus, of which the following is a specification.

This invention relates to refrigerating apparatus and particularly to refrigerating apparatus of the compression type.

One of the objects of the invention is to provide a compression type apparatus with an arrangement of an air cooled condenser that is particularly efficient and sightly.

Another object of the invention is to provide sectional expansion and condenser coils to facilitate varying the capacity of the apparatus to suit conditions.

Another object of the invention is to provide a refrigerating unit in which a single support carries parts of the apparatus on top of it and other parts suspended below it.

Other objects of the invention will appear from the following description taken in connection with the drawings which form a part of this specification, and in which the figure is a perspective view, with parts cut away, of a refrigerating apparatus built according to this invention.

Referring to the drawing, 10 represents a refrigerator box of conventional form, having a compartment 11 adapted to receive the refrigerating element 12. This compartment is in the upper part of the box and an opening 13 is formed in the top through which said element is inserted.

A base or support 14 of a refrigerating unit rests upon the top of the refrigerator box and the element 12 is suspended therefrom as by the brackets 15. This refrigerating or expansion element of the compression system is in the form of several series of loops of piping detachably connected together so that a section such as 16 of the piping may be easily removed or another section added to vary the capacity of the apparatus. The detachable joints are indicated at 17. By looping the coils as shown several small compartments within the coils

are provided within which pans of water 50 may be placed for freezing for domestic use.

The refrigerating system contemplated herein is designed particularly to use a refrigerant of low boiling point such as sulfur dioxide and the apparatus is designed for air cooling the refrigerant. Since the air at the sides or lower part of the refrigerator box is cooler than that above the box, the condenser 18 in the present invention is arranged at the side extending well down toward the bottom of the box. This condenser is preferably suspended from the base 14 by means of brackets 19 extending laterally from one end of the said base and 60 bars 20 depending from the brackets. Also, the condenser is of sectional form, each section comprising coils of piping 21 vertically extending and detachably connected for varying the capacity or for readily repairing a broken section. The detachable joints are indicated at 22.

On top of the support or base 14 is mounted a compressor or pump 23 together with its operating means which may be a motor 75 24. A connecting belt 25 provides the operative connection. A connecting pipe 26 leads from the compressor to the condenser 18, another pipe 27 leads from the condenser to the expansion coil 12 through an expansion 80 valve 28, and a third pipe 29 leads from the expansion element to the compressor, to complete the circuit.

It will be understood that suitable current may be supplied to the motor 24 which 85 will operate the compressor. The refrigerant will be withdrawn from the expansion coils and compressed and passed into the condenser where it will be cooled. The refrigerant is then passed through the expansion 90 valve 28 into the expansion coil 12 in the compartment 11 where it extracts the heat and cools the refrigerator box.

It will be further understood that the invention is not limited to the details shown 95 in the form herein illustrated and specifically described.

Having thus described my invention, what

I claim and desire to secure by Letters Patent is:

In a refrigerating apparatus, in combination, a refrigerator box having an opening 5 in the top, a support mounted on top of said box over said opening, a compressor and motor on said support, an expansion coil in

said box and connected to said support, brackets extending from said support over the side of the refrigerator box, and a condenser suspended from said brackets. 10

In testimony whereof I affix my signature.

MILTON TIBBETTS.
